UNITED STATES PATENT OFFICE.

CHARLES E. WOOD, OF LOUISVILLE, KENTUCKY.

COMBINED STOVE AND FIRE-PLACE.

SPECIFICATION forming part of Letters Patent No. 465,910, dated December 29, 1891.

Application filed June 5, 1891. Serial No. 395,273. (No model.)

To all whom it may concern:

Be it known that I, CHARLES E. WOOD, a citizen of the United States, residing at Louisville, in the county of Jefferson and State of Kentucky, have invented certain new and useful Improvements in Combined Stoves and Fire-Places; and I do hereby declare the following to be a full, clear, and exact description of the invention, such as will enable others skilled in the art to which it appertains to make and use the same.

This invention relates to open-front stoves.

Heretofore it has been common to construct stoves having metallic sides and fire-brick linings. It has also been common to face common fire-places with fire-brick, and it is a well-known fact that the middle of the sides of combustion-chambers become more highly heated and sooner burned out or warped in service than the corners, owing to the fact that heated air when in motion goes in curved lines, which avoid internal corners and impinge strongly against the middle of the sides.

The object of my invention is to adapt a skeleton frame to support and protect the edges of fire-bricks and to form, in conjunction therewith and with other parts, a cooking-stove which shall be readily convertible into an open fire-place.

To this end my invention consists in the construction and combination of parts forming a combined stove and fire-place hereinafter described and claimed, reference being had to the accompanying drawings, in which—

Figure I is a front view showing my invention either as a cooking-stove or fire-place. Fig. II is a transverse vertical section of the same at the line α of Fig. I, showing my invention in service as a stove. Fig. III is also a transverse vertical section taken at the line α and showing my invention in service as an open fire-place. Fig. IV is a top view of the stove, partly in horizontal section. Fig. V is a perspective view of the skeleton frame of my stove and fire-place. Fig. VI is a transverse vertical section showing a modification of my invention. Fig. VII is a longitudinal vertical section at 8, Fig. VI.

10 represents a skeleton frame, which is one of the characteristics of my invention. It will be seen that this frame comprises three

longitudinal bars 11, 12, and 13, two corner-posts 14, a middle post 15, six horizontal bars numbered in pairs, respectively, 16, 17, 55 and 18, and two braces 19.

All the above-described portions are cast in one single piece with bosses 20, projecting inward at the corners of all joints to strengthen the same. This frame is adapted to set 60 freely within the opening which is left for a fire-place by the chimney-builders, and to have placed around it fire-bricks 21, 22, 23, and 24, each of the said bricks being so proportioned that it will rest against the outside 65 of the frame and have its edges protected and concealed by the frame. There may be either one or two bricks 21, forming the lower portion of the back, and if there are two their adjacent edges will be covered and protected 70 by the middle post 15 of the frame.

25 represents bosses projecting rearward from the frame and notched in their upper sides to receive the trunnions 26 of the lower damper 27. The upper back brick 24 is preferably all in one piece, because being farther from the fire it will not be so soon burned out, and it is fitted to rest upon the projecting bosses 25 over the trunnions 26, thereby holding the damper 27 in its bearings. 80

28 represents the grate, which I prefer to cast in one piece with a front top edge 29, projecting at its ends 30 to rest in suitable notches in the middle cross-bar 17 and to be held from working forward by the usual fire-place casing 38. The inner corner of the upper face of the said cross-bar 17 and of the longitudinal bar 13 and of the front edge bar 29 is grooved to form a ledge, within and upon which the top pieces 31 of the stove may 90 rest flush with the top of the said bar. These top pieces may be formed like the usual removable top pieces of a stove with the adjacent edges curved to form circular openings with ledges to receive common stove-lids 32. 95

33 is an ash-pan fitted to slide freely upon the bottom 34 of the fire-place, which may be made of brick or stone, as usual.

35 is the upper damper, which may be made in the usual form, such as the gridiron shape 100 shown in Figs. VI and VII; but I prefer the damper shaped like a single gate pivoted at its ends 36 in a removable portion 37 of the frame, as shown in Figs. II and III. I pro-

vide this damper with a ratchet-shaped brace 39, pivoted at its upper end to the damper and the ratchet-teeth adapted to engage a stud 40, which projects from the inner side of 5 the main frame 10.

41 is a handle whereby the brace 39 may be disengaged from the stud 40, the damper be raised, and the brace be engaged with the said stud at the notch required to hold the 10 damper open at the desired elevation; or by working this handle 41 the brace may be disengaged from the stud and the damper be closed tight down.

42 is a ratchet-toothed brace pivoted to the 15 lower damper 27 and adapted to engage a projecting tooth 43 of the frame to hold the said lower damper open to any amount required. The frame 37 of the upper damper is fitted to engage the main frame 10 by a 20 dovetail joint 44.

In fitting up a fire-place according to my invention the main frame 10 and the top frame 37 are fitted together and placed in the opening for the fire-place. Then the fire-bricks 21 22 are to be placed against the back 25 and sides of the frame and the space behind them is to be filled in with sand. The upper end bricks 23 are then to be placed against the frame and wedged in with pieces of loose 30 brick. The back brick 24 is entirely supported by standing upon the bosses 25 and leaning forward against the braces 19, leaving an opening 45 for a flue between this brick and the back 46 of the chimney. The 35 lower damper 27 is to be placed in its bearings before the brick 24 is put in. The grate 28 and damper 35 may now be placed in position. Then the front casing 38 of the fire-place is placed and fastened, as usual, holding the said 40 grate and damper in their bearings. It will be readily understood that as no cement or mortar is used in the setting of this frame the parts may be removed in the reverse order to that above stated for fitting the fire-place, so that if 45 any bricks should become burned out there is no great difficulty in replacing them, since there is nothing about the whole device which is permanently fastened to the chimney. When the top pieces 31 and the lids 32 are in place, 50 this invention is an open-front stove, whose draft is through the flue 45, controlled by the damper 27, and at such times the upper damper 35 may be entirely closed to force all the draft through the flue 45, or it may be a little open 55 to permit the escape of any smoke or disagreeable odors which may result from cooking on the stove, thus rendering it particularly applicable for use in flats and other dwellings where a room occupied by the in-

habitants must also serve as a kitchen or 60 cooking-room. Now if the top pieces 31 and lids 32 of the stove be removed the device becomes an open fire-place, whose draft may be controlled wholly by the upper damper 35, the products of combustion passing freely 65 through the opening which was formerly covered by the top of the stove. At the same time the lower damper 27 may be kept open when a low fire is desired and but little heat required in the room. In houses where the 70 casing 38 has already been set my whole device may be easily placed in behind it without removing it.

Having thus fully described my invention, what I believe to be new, and desire to secure 75 by Letters Patent, is the following:

1. The combination, in fire-places, of a skeleton frame having the longitudinal bars 12 and 13, located as described, and the projecting bosses 25, notched in their upper sides, a 80 damper fitted to close the space between the said bars and provided with trunnions to fit the said notches as bearings, and a brick fitted to rest upon the said bosses on the frame and hold the damper in, substantially as described. 85

2. The combination of the fire-place frame 10 in skeleton form, the side bricks 21 and 22, fitted to the outer sides of the frame, the back bricks 23 and 24, fitted to the back of the frame with an opening between them, and a 90 flue leading therefrom behind the brick 23, and a damper for said opening, substantially as described.

3. The combination of a fire-place frame in skeleton form, a fire-grate fitted thereto, the 95 top of the grate and that portion of the frame on the same level being internally grooved as a ledge to receive a top, top pieces removably fitted to the said ledge, lids fitted to the top, a back fixed permanently above the top, a 100 flue behind the said back, and openings leading to the flue both above and below the back, substantially as described.

4. The combination, in a fire-place and stove, of a stove portion having a removable top and 105 a dampered outlet below the said top into a chimney-flue, a permanent fire-place back fixed above the top of the stove and in front of the said flue, and a dampered inlet to the said flue above the said back, substantially 110 as described.

In testimony whereof I affix my signature in presence of two witnesses.

CHARLES E. WOOD.
